DESIGN FOR A PAPER DOLL

Priscilla Burg and Prudence Burg, Syracuse, N. Y.

Application September 29, 1937, Serial No. 71,867

Term of patent 7 years

To all whom it may concern:

Be it known that we, Priscilla Burg and Prudence Burg, citizens of the United States of America, residing at Syracuse, New York, have invented a new, original, and ornamental Design for a Paper Doll, of which the following is a specification, reference being had to the accompanying drawing, forming part thereof, in which:

The dominant feature of our design is the appearance of the head, which is in the form of a loop of paper, as shown more particularly in Figure 2.

We claim:

The ornamental design for a paper doll as shown and described.
